CLAIM

The ornamental design for a point-of-sale device docking station, as shown and described.

DESCRIPTION

FIG. 1 is a front right upper perspective view of a point-of-sale device docking station showing the new design.

FIG. 2 is a rear left lower perspective view of the point-of-sale device docking station of FIG. 1.

FIG. 3 is a front view of the point-of-sale device docking station of FIG. 1.

FIG. 4 is a rear view of the point-of-sale device docking station of FIG. 1.

FIG. 5 is a right side view of the point-of-sale device docking station of FIG. 1.

FIG. 6 is a left side view of the point-of-sale device docking station of FIG. 1.

FIG. 7 is an enlarged top view of the point-of-sale device docking station of FIG. 1; and,

FIG. 8 is an enlarged bottom view of the point-of-sale device docking station of FIG. 1.

The features shown in broken lines depict portions of the point-of-sale device docking station form no part of the claimed design.

1 Claim, 8 Drawing Sheets
